UNITED STATES PATENT OFFICE.

EDWARD J. GULICK, OF ELKHART, INDIANA.

TAMPION PAD.

Application filed April 12, 1926. Serial No. 101,327.

REISSUED

My invention relates to improvements in wind musical instruments of the saxophone class, and the like, and especially to tampion pads therefor.

- 5 In the construction and design of saxophone pads and keys it is of primary importance that they be of simple construction and that the contact of metal on metal be eliminated.
- 10 The main object of my invention is to provide a saxophone tampion pad which is simple, cheap, very effective, and easily made and assembled. Another object of the invention is to provide a saxophone 15 tampion pad which can be readily pressed into the pad-cup and retained therein by the tight fit.

Other objects of the invention are mentioned and described herein.

- 20 The preferred embodiment of my invention is illustrated in the accompanying drawing, in which Figure 1 illustrates a fragment of a saxophone to which the invention is applied; Fig. 2 is a cross-section 25 taken through the saxophone body at one of the tone openings and showing the key and key pad; Fig. 3 is a cross section through the tampion pad and tampion prior to assembly thereof; Fig. 4 is a plan 30 view of the pad ring; and Fig. 5 is a section taken on line 5—5 of Fig. 4.

Similar numerals of reference indicate like parts throughout the several views on the drawing.

- 35 Referring to the details of the drawing the numeral 1 indicates a saxophone fragment which may be of the usual tapered tubular construction, and which is provided with a plurality of the usual lateral tone 40 openings 2, the flanged up-standing rim 3 whereof constitutes the seat for the key and pad hereinafter described.

The numeral 4 indicates the cup-like key body provided with the annular depending 45 peripheral flange 5 within which the key pad assembly herein described is adapted to be removably mounted.

50 My improved key pad assembly comprises the annular ringlike pad carrier 6, the felt pad, composed of the two annular elements 7 and 8, of which the latter may be ringlike, and the kid leather cover 9 adapted to be suitably secured about the pad and ring

after the two part pad has been fitted within the carrier 6. As illustrated, a draw string 55 10 is shown to secure the cover 9 about the pad and carrier, but any suitable adhesive may be used for that purpose when desired.

The pad carrier 6 is preferably made of ductile sheet metal and is provided with the 60 outwardly extending angular flange 11, the body of said carrier being slightly less in diameter than the interior diameter of the pad-cup 4 to insure a tight fit of the assembled pad when the latter is pressed into 65 said pad-cup, and whereby said pad assembly is firmly retained within said pad-cup by said tight fit, and in which position of the pad assembly the flange 11 of the pad carrier serves as a stop element to properly 70 position the pad within the pad-cup.

Normally, the pad assembly described is held snugly within the pad-cup 4, but it may be readily removed therefrom by the use of a knife blade by inserting the point thereof 75 between the flange 11 and the edge of the key body and prying thereon.

I claim:

1. In a wind musical instrument of the class described, the combination of a pad-cup provided with a peripheral depending flange, and a key pad assembly mounted within said pad-cup, said pad assembly comprising an annular pad carrier provided with an angular outwardly extending 85 peripheral flange, a pad arranged within said carrier, and a flexible pad cover secured about said pad and carrier, said key pad assembly being fitted tightly within said pad-cup and retained therein wholly by 90 said tight fit.

2. In a wind musical instrument of the class described, the combination of a pad-cup provided with a peripheral depending flange, and a key pad assembly mounted 95 within said pad-cup, said pad assembly comprising a ring-like carrier provided with an angular outwardly extending peripheral flange, a pad arranged within said carrier, and a flexible pad cover secured about 100 said pad and carrier, said key pad assembly being fitted tightly within said pad-cup and retained therein wholly by said tight fit, and said pad carrier flange engaging the edge of said key body flange as a stop element. 105

3. In a wind musical instrument of the character described, the combination of a pad-cup provided with an endless peripheral depending flange to form a cup-like key body, and a key-pad assembly arranged and fitted tightly within said pad-cup and against said depending flange and retained

therein wholly by said tight fit with said flange, said pad assembly including a metal pad carrier and a yieldable pad body.

In witness whereof I have hereunto affixed my signature this 8th day of April, 1926.

EDWARD J. GULICK.
